United States Patent Office

Des. 194,605
Patented Feb. 19, 1963

194,605

DOCUMENT SORTER CABINET

Charles P. Breed and Edward H. McCauley, both of
P.O. Box 122, Dallas, Tex.

Filed Oct. 17, 1962, Ser. No. 72,138

Term of patent 14 years

(Cl. D26—5)

FIG. 1

FIG. 3

FIG. 1 is a perspective view of a document sorter cabinet; showing our new design;

FIG. 2 is a rear view thereof; and

FIG. 3 is a left end view thereof.

We claim:

The ornamental design for a document sorter cabinet, as shown.
